DESIGN FOR A CRUCIFIXION CROSS OR SIMILAR ARTICLE

Benjamin E. Puciloski, Cicero, Ill.

Application March 30, 1935, Serial No. 56,136

Term of patent 7 years

To all whom it may concern:

Be it known that I, Benjamin E. Puciloski, a citizen of the United States and residing in the village of Cicero, in the county of Cook and State of Illinois, have invented a new, original, and ornamental Design for a Crucifixion Cross or Similar Article, of which the following is the specification, reference being had to the accompanying drawing, forming a part thereof.

On the drawing:

Fig. 1 shows a front elevation of my crucifixion cross.

Fig. 2 is a cross sectional view on line 2—2, Fig. 1.

I claim:

The ornamental design for a crucifixion cross or similar article, substantially as shown.

BENJ. E. PUCILOSKI.
